UNITED STATES PATENT OFFICE.

ARTHUR KAHLOW, OF MAYVILLE, WISCONSIN.

HANDLE FOR TRAVELING BAGS.

Application filed March 14, 1922. Serial No. 543,575.

To all whom it may concern:

Be it known that I, ARTHUR KAHLOW, a citizen of the United States, and resident of Mayville, in the county of Dodge and State 5 of Wisconsin, have invented certain new and useful Improvements in Handles for Traveling Bags; and I do hereby declare that the following is a full, clear, and exact description thereof.

10 The invention relates to new and useful improvements in handles for traveling or Gladstone bags and more particularly to the type comprising a grip member covered with leather, or other sheathing material.

15 The invention comprises a wire reinforcement, a rubber body member surrounding the wire, a leather sheathing, a ferrule receiving the ends of the handle and secured by suitable threads to the wire, the ferrule being 20 pivoted to a base plate riveted to the frame of the bag and having a depending hook adapted to be received in a slot in the opposed frame for holding the two frames in contacting relation.

25 The primary object of the invention is the provision of a structure wherein the wire reinforcement is held rigid with the ferrule, the threaded relationship preventing a tendency to tear loose. There is no relative movement 30 between the two parts and consequently there is no tendency to tear away the wire from the rubber body. In addition to this feature of rigidity, the structure has the obvious advantage of cushioning the 35 handle upon the hand, a desirable stiffness thereof being maintained.

An important object of the invention is accomplished by the depending hook structure, which facilitates a ready affixation of 40 one frame member to another and a ready detachment of the parts.

The mere manual movement of the frame between the end of the hook and the other frame member suffices for the securing of 45 the parts. When the frame members are in proper closed position, they are secure with respect to each other, a locking relationship being established, the cooperation of the hook with the rigid portions of the frames providing a strong structure capable of sustaining great weight without tendency to tear loose.

An advantage is the concealing of the hook.

With the above and other objects in view, 55 which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of the present invention constructed according to the best mode I have so far devised for the practical application of the principles thereof, and in 70 which:

Figure 1 is a side elevation of the device.

Figure 2 is a cross section thereof on the line 2—2 of Figure 1.

Metallic frame member 10 is enveloped by 75 a loop 11 of leather or other suitable material of bag 12 and base plates 13, 13' are secured thereto by studs 14, 14'. Depending hook 15 is directed laterally, as shown in Figure 2, through a slot 16 in metallic frame piece 10' 80 covered by leather 11'. The frame pieces may be readily moved into the position shown in Figure 2, frame member 10' being merely inserted in the space between the end of hook 15 and the edge of frame 10, the 85 arrangement of parts facilitating the centering action.

In the assembled position, the drawing downwardly of the sides of the bag by the weight of the material supported, tends to 90 lock all members slightly in assembled relation so the frame members may be provided with other suitable locking devices, as is customary.

From base plates 13, 13' apertured lugs 17, 95 17' extend upwardly and are received between ears 18 on the one side and 19 on the other side and pivoted thereto by pivots 25, 25'. These ears are integral with ferrule 20, 20' into which wire reinforcement 21 is 100 threaded, as shown at 22, the wire being enveloped in elastic body 23 encased in suitable sheathing 24. As shown, the sheathing and body extend within and are gripped by the ferrules. The threaded relationship of wire 21 and ferrule 22 precludes possibility 105 of relative movement between the parts and makes the connection rigid. Looseness, or

movability, would result in a tendency for the parts to tear away, thus tending to render the handle useless.

The entire structure, therefore, of wire reinforcement, ferrule, and depending hook is especially strong and adapted to stand severe usage.

I claim:

1. The combination of a metallic frame member, a base member, a depending hook extending downwardly thru said metallic frame member, a second metallic member, said second frame member having a slot therein for the reception of said depending hook, said depending hook being adapted to hold said frame members in close contactual relationship, a handle, and means pivotally connecting said handle to said base member.

2. The combination of a metallic frame member, a cover therefor, a base member, a depending hook extending downwardly through said cover and said metallic frame member, a second metallic frame member, a cover therefor, said frame member and cover having a slot therein for the reception of

said depending hook, said depending hook being adapted to hold said frame members in close contactual relationship, a lug on said base plate, and a handle pivotally secured to said lug.

3. The combination of a wire reinforcement, an elastic body, a sheathing therefor, a ferrule receiving said reinforcement, said body, and said sheathing and engaged in threaded relationship with said reinforcement, a pair of ears on said ferrule, a base plate, a lug thereon, a pivot directed through said lug and said ears, a hook depending from said base plate, a metallic frame member, a cover therefor, means securing said frame member to said base plate, said hook extending through said frame member and said cover, a second metallic frame member, and a second cover therefor, said second metallic frame member having a slot therein for the reception of said hook.

In testimony that I claim the foregoing I have hereunto set my hand at Mayville, in the county of Dodge and State of Wisconsin.

ARTHUR KAHLOW.
